NEEDLE

Application filed August 23, 1929. Serial No. 388,020.

This invention which relates generally to needles for darning or embroidering is concerned particularly with certain features of construction by which such needles are rendered adaptable for producing a stitching of novel and attractive character. By way of exemplification, I have illustrated in the accompanying drawings a needle having certain improved features, Figures 1 and 2 being face and edge views thereof in elevation, and Figures 3, 4 and 5 examples of single, double and cross weaving or stitching which may be performed with such a needle.

Referring now to Figures 1 and 2, the present needle A is shown in the general form of a thin flexible blade having one end suitably shaped or pointed at 6 for insertion into the work. The opposite needle end or head 7 which may be very slightly wider than elsewhere is preferably rounded, and close to this end of the needle, I provide two or more slots 8—8, side by side or offset, forming eyes through which to receive the darning or embroidering yarn or cotton which is to be woven or stitched into the work.

The opposite edges of the needle are substantially parallel, and the width of the needle, as compared with others commonly in use, is considerable. The other cross sectional dimension of the needle, that is its thickness, may be uniform, or substantially so, from end to end. Because of the unusual width of the needle it is possible to obtain from the use thereof certain interesting results, but the work or fabric which the needle is required to penetrate in performing a darning or embroidering operation should desirably have its warp and/or woof threads spaced apart a distance which corresponds generally to the width of the needle. Such a fabric construction is suggested in Figures 3, 4 and 5 to which further reference will now be made.

The fabric material to be worked with the needle of this invention permits of several variations in the weaving which is performed. By the cross marks in Figures 3, 4 and 5, I have indicated diagrammatically the juncture points of the interwoven warp and woof threads which together compose a

55 fabric material with which my improved needle may be used to advantage. The spacing of these juncture points which is determined in part by the constituent threads of the fabric corresponds generally to the width of the needle, as will be noted from these figures of the drawings. Inserted into the eyes 8—8 of the needle are duplex threads *a* and *b* of yarn, cotton, or the like, and such threads when worked in the fabric lie side by side, as at *x* and *y*. The number of eyes to be formed in the needle will be determined according to the number of threads to be handled by the needle at one time, and consequently more than two eyes, if desired, may be employed.

60 In the operation of my needle with duplex threads, as above suggested, a single weaving may be performed. Such an operation is illustrated in Fig. 3 wherein it will be noted the needle is worked always in a single direction to draw the duplex threads in and out in parallel rows, the exposed portions of the darning or weaving being desirably in the form of staggered squares to provide a tessellated effect. By double weaving, as suggested in Figure 4, the fabric material is covered completely with squares of the embroidery or darning thread which are disposed transversely in alternation. A further example of possible weaving is set forth 65 in Figure 5 wherein I have shown a cross stitch, one that is produced by working the needle and duplex threads diagonally crosswise back and forth to provide open squares or diamonds bordered by stitching that tends to expand slightly in its middle portions which are remote from the juncture points of the woven threads forming the fabric material to which such stitching is applied. These three examples of weaving or stitching performed by embroidering or darning operations with the present needle, are suggested of others which need not be described in detail.

70 75 80 85 90 95 100 My improved needle is characterized by the provision of plural slots, side by side, or offset, forming eyes for receiving a multiplicity of threads. In constructing such a needle, it is of advantage to employ flat stock

which is more readily susceptible to die or stamping operations. A needle of this flattened character also possesses the advantages of spreading more easily the warp and/or woof threads of the fabric material, and of sliding with less resistance through the spaces thereby provided. In so doing the needle may be flexed, as required in the single direction of its thickness. Furthermore, the substantial width of the needle tends always to facilitate its use in the same plane; that is, any twisting or turning thereof in the weaving or darning operation is automatically resisted. This is of importance where, as in the present case, duplex threads are to be worked, and the smooth, parallel, and non-twisted disposition of such threads is a contributing factor in the appearance of the finished product.

20 I claim:

A needle of the kind described, relatively flat and flexible in one direction only, and provided adjacent one end with transversely spaced unconnected eyes for receiving and drawing a multiplicity of threads between the threads of a fabric without twisting of the drawn threads.

25 In testimony whereof, I have hereunto set my hand this 7th day of August, 1929.

30 LEONARD G. DAHM.
